DESIGN FOR A TEXTILE FABRIC

Robert Francis Allgor, Bergenfield, N. J.

Application November 28, 1940, Serial No. 96,894

Term of patent 3½ years

To all whom it may concern:

Be it known that I, Robert Francis Allgor, a citizen of the United States of America, residing in Bergenfield, county of Bergen and State of New Jersey, have invented a new, original, and ornamental Design for a Textile Fabric, of which the following is a specification, reference being had to the accompanying drawing, forming part thereof, wherein,

The drawing is a plan view of a piece of textile fabric, the design of which comprises an all over pattern extending from the border shown at the top of the figure to the selvage at the opposite edge.

I claim:

The ornamental design for a textile fabric, substantially as shown and described.

ROBERT FRANCIS ALLGOR.
